COMBINED CIGARETTE EXTINGUISHER
AND ASH TRAY

Charles A. T. Agee, Collingswood, N. J.

Application January 6, 1945, Serial No. 571,607

7 Claims. (Cl. 131—235)

1

This invention relates to combined cigarette extinguishers and ash trays.

Both from the standpoint of fire hazard as well as from annoyance to the olfactory nerves of those present, a smouldering cigarette stump is at least undesirable, and positive extinction of all cigarettes before disposition in an ash tray is very advantageous.

In my earlier patent, No. 2,256,420, of September 16, 1941, these advantages of complete and prompt cigarette extinction are stressed and enlarged upon, and a system is proposed which has given excellent results. It has been found, however, that there are certain more or less disadvantageous features in the earlier construction, which includes complexity of structure and therefore unnecessary expense, usual requirement for use of at least three fingers for successful operation, and the necessity for bringing a slot in an area of unslotted material extending on each side of the slot under an aperture to permit the extinguished cigarette to drop into a receptacle.

It is among the objects of this invention: to improve the art of cigarette extinguishers; to avoid disadvantages of my earlier patent aforesaid; to improve the appearance of the combined instrumentality as recited; to provide a device controlled by a lever action by an arm slidable in a vertical slot in place of the plunger device of the past; to provide a simple and cheap combined extinguisher and ash tray; to provide a cheap combined extinguisher and tray which can be made of plastics as well as of metal or other suitable material, if desired; and many other objects and advantages of the invention will become more apparent as the description proceeds.

In the accompanying drawings forming part of this description:

Fig. 1 represents a perspective of the preferred form of the combined instrumentality of the invention. Fig. 2 represents a transverse vertical section therethrough. Fig. 3 represents a fragmentary vertical section taken on line 3—3 of Fig. 2. Fig. 4 represents a fragmentary section taken on line 4—4 of Fig. 3. Fig. 5 represents a fragmentary section taken on line 5—5 of Fig. 3. Fig. 6 represents a fragmentary horizontal section taken on line 6—6 of Fig. 4. Fig. 7 represents a fragmentary transverse section through a modified form of actuating device mounting.

In a preferred embodiment, the invention comprises an open ended tray 10 comprising a rim 11 and depending skirt 12 to which by any suitable means, the receptacle 14 of any desired shape or capacity can be removably attached. Illustratively as illustrated in detail in Fig. 5, the lock-

2

ing device comprises a stud 9 on the receptacle 14, removably engaging an aperture 13 on the skirt 12. The rim is bisected fore and aft by a median leg or rib 15 extending from the inner side of the front portion of the rim to a rear rim protuberance 16 comprising the transversely oval portions 17 and 18, symmetrical of the leg 15, and having the transversely spaced apertures 20 and 21. Cigarette-stump receiving cylinders 22 and 23 are slidably mounted in the respective apertures and each is threaded into respective threaded apertures 19 in the plate 24 of a casting. The casting has integral portions 26 disposed between the plate 24 and the under surface of the enlargement 16 and are held tightly thereagainst by shoulders 27 on the threaded tubes 22 and 23 bearing against the outer surface of the portions 16. A slide or false bottom 28 is provided having an elongated guide slot 30 longitudinally disposed to be engaged by a supporting and connecting screw 31 having an enlarged head 32 engaging the lower surface of the slide 28 to hold the slide against the lower surface of the plate 24. The slide has a flattened front edge 33, provided with two semi-cylindrical scallops 34, arranged, in the fully retracted position of the slide, to register with both apertures 19 and thus to permit cigarette stumps which had rested against the slide to drop through into the receptacle 14 below.

The slide has a reduced neck portion 35 disposed in parallel spaced alignment with the median rib 15 for a short distance so as to be substantially covered by the latter in vertical projection, and has a working slot 36 in alignment with its guide slot 30.

In order to provide a simple single actuating element for controlling the position of the slide 28, the side walls 37 and 38 of the median rib 40 are extended to form a pair of spaced apertured ears 40. A bell crank lever 41 has one arm 42 working in the slot 36 and the other arm 43 projecting through and guided by a vertical slot 44 in the skirt 12 of the tray 10. The bell crank is journaled on a pivot pin 45 extending between the ears 40 by means of a pivotal sleeve 46 on the bell crank. The pin 45 may comprise a rivet or a bolt and nut arrangement or the like. If desired, the bell crank can be mounted on a separate mounting agency 49 and the latter removably disposed on the median rib 15 as shown in Fig. 7. A thumb or finger piece 47 is mounted on the free end of bell crank arm 43 and it will be seen that the finger piece can be elevated and the bell crank swung to the dotted line position of Fig. 2, as a simple one finger manipulation, or as

a simple squeeze between the finger piece 47 and the upper surface of the tray 10, if the combined device is not anchored to a rigid support.

To return the slide 28 to its normally closed position while also repositioning the bell crank lever handle for operation toward slide retraction, a tension spring 48 is connected at one end to some fixed point on the median rib such as to the bracket 50 either struck out of or attached to the rib, and to the bell crank arm 42.

It will be understood that in many cases the device will be formed of molded plastic, although metal or even glass for certain parts may be preferred for certain types of uses.

Preferably, the device is fastened to a desk or built into or fastened on automotive equipment or the like so as to afford a rigid support.

The user of the device after lighting a cigarette and smoking as much thereof as is desired, simply drops the stump or butt lighted end foremost into one or the other of the cylindrical tubes 22 or 23 until the lighted end abuts the false bottom comprised of the solid portion of the slide 28, in which position, without any grinding or force upon the exposed outer end of the stump, owing to the relatively close diametric relationship of the cigarette and the tube the light is promptly extinguished by lack of support for combustion. This may take a mere two or three seconds. Pursuant to extinction thereof the user then simply flips up the handle 41 retracting the slide 28 until the semi-cylindrical scallops register with the semi-cylindrical half of either the through aperture 19 adjacent to the screw 31 of the tube 22 or 23 upon the attainment of which position the extinguished cigarette stump drops down through the registering cylinder 22 or 23, aperture 19, scallop 34, and into the receptacle 14. Smouldering is impossible and the fire hazard is minimized.

Obviously, the exact number of stump-receiving tubes operable by a single slide device as shown need not be the exact number illustrated, as there may be more or less, as the occasion demands.

Having thus described my invention, I claim:

1. A cigarette extinguisher comprising a tray, a casting comprising a plate and spacing means, said spacing means on the casting extending between the plate and the under surface of the tray, said tray having an aperture and said plate having a threaded aperture, a tube having a shoulder and a threaded end and disposed in the aperture in the tray and threaded into the aperture in the plate to anchor the plate and tray together by forcing said spacing means against the under side of the tray while engaging the shoulder against the outer surface thereof, and a false bottom slidable on the plate to cover and uncover the tube and threaded opening in the plate.

2. A cigarette extinguisher comprising a tray, a casting comprising a plate and spacing means, said spacing means on the casting extending between the plate and the under surface of the tray, said tray having an aperture and said plate having a threaded aperture, a tube having a shoulder and a threaded end and disposed in the aperture in the tray and threaded into the aperture in the plate to anchor the plate and tray together by forcing said spacing means against the under side of the tray while engaging the shoulder against the outer surface thereof, a false bottom slidable on the plate to cover and uncover the tube and threaded opening in the plate, said tray having a vertical slot, and said

bottom having a working slot, a bell crank lever pivoted to the tray having one arm riding in said vertical slot and the other arm riding in said working slot, and resilient means urging the slideable bottom toward closure of the opening of the tube and threaded opening.

3. A cigarette extinguisher comprising a tray having a strengthening rib dividing the tray into spaced ash receiving openings, means establishing a cigarette extinguishing tube with an axis substantially normal to a plane of the rib, a slide, means for supporting the slide for guided movements in a line substantially parallel to the longitudinal axis of said rib to open and close the bottom of the tube, and means pivoted on and substantially concealed by the rib when viewed from directly overhead for actuating the slide, said pivoted means being on a pivot axis parallel to said plane.

20 4. A cigarette extinguisher comprising a tray having a strengthening rib dividing the tray into spaced ash receiving openings, means establishing a cigarette extinguishing tube with an axis substantially normal to a plane of the rib, a slide, means for supporting the slide for guided movements in a line substantially parallel to the longitudinal axis of said rib to open and close the bottom of the tube, means pivoted on and substantially concealed by the rib when viewed

25 from directly overhead for actuating the slide, said pivoted means being on a pivot axis parallel to said plane, said pivoted means comprising a bell crank lever pivoted to the rib inwardly of the tray edges, means engaging one arm of the bell crank with the slide to move same as the bell crank is swung, and means for actuating the other arm of the bell crank by the operator.

5. A cigarette extinguisher comprising a tray having a strengthening rib dividing the tray into spaced ash receiving openings, means establishing a cigarette extinguishing tube with an axis substantially normal to a plane of the rib, a slide, means for supporting the slide for guided movements in a line substantially parallel to the longitudinal axis of said rib to open and close the bottom of the tube, and means pivoted on and substantially concealed by the rib when viewed from directly overhead for actuating the slide, said pivoted means being on a pivot axis parallel to said plane, said slide having a solid portion to close the tube bottom and having an edge provided with a semi-cylindrical recess arranged to register with the correspondingly curved portion of the tube in the retracted position of the slide to permit an extinguished cigarette to fall through the tube.

6. A cigarette extinguisher comprising a tray having a strengthening rib dividing the tray into spaced ash receiving openings, means establishing a cigarette extinguishing tube with an axis substantially normal to a plane of the rib, a slide, means for supporting the slide for guided movements in a line substantially parallel to the longitudinal axis of said rib to open and close the bottom of the tube, and means pivoted on and substantially concealed by the rib when viewed from directly overhead for actuating the slide, said pivoted means being on a pivot axis parallel to said plane, said tray having a depending skirt with a vertical slot, said slide having a longitudinal slot, and said means for actuating the slide comprising a bell crank lever having one arm guided in the vertical slot and the other working in the longitudinal slot, and being pivoted to the rib on said tray.

7. A cigarette extinguisher comprising a tray having a strengthening rib dividing the tray into spaced ash receiving openings, means establishing a cigarette extinguishing tube with an axis substantially normal to a plane of the rib, a slide, means for supporting the slide for guided movements in a line substantially parallel to the longitudinal axis of said rib to open and close the bottom of the tube, means pivoted on and substantially concealed by the rib when viewed from directly overhead for actuating the slide, said pivoted means being on a pivot axis parallel to said plane, said tray having a depending skirt with a vertical slot, said slide having a horizontal slot, and said means for actuating the slide comprising a bell crank lever having one arm guided in the vertical slot and the other working in the horizontal slot, and being pivoted on the rib on said tray, and a tension spring to pull the slide in one direction.
